N. L. TOMLINSON, OF NEW YORK, N. Y.

Letters Patent No. 86,043, dated January 19, 1869.

IMPROVEMENT IN STEERING-APPARATUS.

The Schedule referred to in these Letters Patent and making part of the same.

To all whom it may concern:

Be it known that I, N. L. TOMLINSON, of the city, county, and State of New York, have invented a new and improved Steering-Apparatus; and I do hereby declare that the following is a full, clear, and exact description thereof, which will enable others skilled in the art to make and use the same, reference being had to the accompanying drawings, forming part of this specification, in which—

Figure 1 represents a side elevation, partly in section, of my improved steering-apparatus.

Figure 2 is a plan or top view of a modification of the same.

Similar letters of reference indicate corresponding parts.

This invention relates to a new steering-apparatus for marine vessels of all kinds; and consists in the use of a horizontal perforated plate, projecting from the rudder-post, and of a small wheel, carrying knobs, that fit into the perforations of the aforesaid plate, the said wheel being mounted on the same horizontal shaft on which the steering-wheel is mounted.

The invention also consists in connecting the said plate and shaft by means of a clamp or pendant, which is suspended from the shaft, and catches around a segmental rib, projecting from the under side of the plate.

A, in the drawing, represents the upper end of a rudder-post, or a block or beam secured upon the rudder-post.

B represents a metal plate, of segmental or other form, fastened to the post A in any suitable manner, so as to project horizontally from the same.

The best manner of fastening the plate is to make the upper end of the post polygonal, and to form a corresponding perforation in the plate, as shown in fig. 2.

The plate B is provided with a series of perforations or cavities, *a a*, which are arranged in the arc of a circle, struck from the axis of the rudder-post as centre.

C represents a horizontal shaft, mounted in suitable bearings, so as to be above the plate B, as shown.

I prefer to hang the shaft C in a pin, *b*, which is

swivelled in the upper end of the rudder-post, and in a fixed support, *c*, as is clearly shown in fig. 1. However, both supports may be fixed and stationary, if desired.

On the shaft C is mounted a small wheel, D, from the rim of which teeth or pins, *d d*, project, that fit into the holes of the plate B, as shown in fig. 1. Thus, by turning the shaft C, by means of a steering-wheel, F, which may be mounted on the fore or aft end of the shaft, as is respectively indicated in figs. 1 and 2, the wheel B will be set in motion and the rudder-post will be turned.

The wheel D is too small, in proportion to the radius of the plate B, to allow the shaft C to be turned by means of the plate, and therefore the rudder and the whole steering-apparatus will always remain spontaneously locked in whatever position the rudder may stand. The employment of other fastening-devices is thereby made superfluous.

The outer edge of the plate B is curved, parallel to the row of holes *a a*, and on its under side is formed a segmental rib, *e*.

E represents a hook or pendant, hung on the shaft C, and catching around the rib *e*, as shown, so as to hold the plate B always against the edge of the wheel D, so that by strain or shrinkage they cannot be drawn apart.

Having thus described my invention,

I claim as new, and desire to secure by Letters Patent—

The segment B, having upon its under side the rib *e*, fitting in and supported by the hook E, pendent from the shaft C, which turns in the outer bearing *c*, and the bearing *b*, swivelled in the rudder-post, said segment being perforated to receive the pins *d* of the small wheel D, which is also hung upon shaft C, all constructed and arranged to operate as herein described, for the purpose specified.

N. L. TOMLINSON.
